UNITED STATES PATENT OFFICE.

WILLIAM R. BARTON, OF BRIDGEWATER, MASS., ASSIGNOR OF ONE-HALF
TO GEORGE C. HAMMOND, OF PAWTUCKET, R. I.

WELT-TRIMMER.

SPECIFICATION forming part of Letters Patent No. 235,493, dated December 14, 1880.

Application filed August 14, 1880. (Model.)

To all whom it may concern:

Be it known that I, WILLIAM R. BARTON, of Bridgewater, in the county of Plymouth and State of Massachusetts, have invented a new and valuable Improvement in Seam-Welt Trimmers; and I do hereby declare that the following is a full, clear, and exact description of the construction and operation of the same, reference being had to the annexed drawings, 10 making a part of this specification, and to the letters and figures of reference marked thereon.

Figure 1 of the drawings is a representation of a perspective view of this instrument. Fig. 2 is a top view. Fig. 3 is a bottom view. 15 Fig. 4 is a side view of the shank and its head-branch. Fig. 5 is a side view of the removable branch.

This invention has relation to means for trimming seam-welts; and it consists in the 20 construction and novel arrangement of parts, as hereinafter shown and described.

In the accompanying drawings, the letter A designates the shank of this instrument, connected to a handle, B. On the end of the 25 shank is formed one branch, C, of the head, having a curved half-crescent form, somewhat obliquely arranged with reference to the direction of the shank, as shown in the drawings.

This branch C of the head is constructed with 30 a shoulder, a, at the end of the shank, and a bearing-shoulder, b, in the direction of the shank, and offset from the guard-wall c, in which is made a straight groove, d, along the shoulder, and extending to the guard-point e, 35 the outer edge, f, of which is beveled and extends obliquely across the end of the groove, as shown. The end of the guard is rounded and beveled on the inside outward in a flaring manner, as shown at g. A threaded hole, h, is

40 made in the larger rear portion of the head to receive the end of the screw D, which serves to secure the removable branch E. This branch is also provided with a bearing-shoulder, b', on its outer rounded portion, said shoulder being 45 also offset from its inner wall, which is grooved at d along the shoulder to the guard-point e, which is rounded and beveled on its inner and outer edges, the outer beveled guard edge, f, crossing the groove obliquely, as described

above in reference to the rigid portion of the 50 head.

The blade k is a long thin slip of steel with parallel edges, which are seated in the grooves d, which are opposite to each other when the removable portion E is secured to the fixed 55 branch D of the head. The steel blade extends through the head along the shank in rear, and in front along and between the bearings b and b', whereby it is securely held. The under shoulder, b', is usually made somewhat 60 longer than the upper shoulder, extending nearer to the point portion, so that the blade will have a bearing near its cutting extremity z. Along the back rounded portion, m, of the head a central groove, n, is made, the 65 walls of which form running edges s, of somewhat acute form, beveled on their outer surfaces at f, and serving to guide the head in the seam, the welt being received in the intermediate groove.

The branch E of the head can be easily loosened, so that the blade can be removed or adjusted nearer to or farther from the guard points and edges of the head, to cut deep or shallow when brought against the welt.

In sharpening, the blade is designed to be pushed forward clear of the guard in front, so that the guard portion of the head will not be worn or injured, and will therefore be always 75 in good shape, not wearing or cutting the upper when in use.

The blade is beveled on its upper side at the cutting extremity, and its edges are formed square to fit neatly in the grooves d of the head, which are also squared and hold the 85 blade firmly. The guard-points are designed to extend somewhat in front of the cutting-edge, as shown.

I am aware that a welt-trimmer having a fixed jaw and a clamping-jaw secured together by a 90 screw has been used to clamp the knife and hold it in position; but in the instance referred to (Patent No. 8,802, March 23, 1869) the inner faces of the jaws are plain, and the knife is passed through a recess in the rear 95 end of the clamping-jaw. In mine the straight bearing-shoulders b b' and the grooves extending thence to the points e e hold the knife

as rigidly as if it were fixed in the head of the tool.

Having thus fully described my invention, what I claim is—

5 In a welt-trimmer, the combination of the branch C, secured to the shank A, and provided with the elongated offset bearing-shoulder b above its center and a groove, d, extending longitudinally of the branch below said shoulder b, with the removable branch or clamping-jaw E, having an offset bearing-shoulder, b', below its center, extending nearer to the point of the head than the shoulder b,

and a groove, d, above the shoulder b', the set-screw D, and a knife, k, clamped between the 15 shoulders b b', and having the edges resting in the grooves d d, substantially as and for the purposes set forth.

In testimony that I claim the above I have hereunto subscribed my name in the presence 20 of two witnesses.

WILLIAM RANDAL BARTON.
